UNITED STATES PATENT OFFICE.

JACOB V. LEYDIG, OF GREENE, IOWA.

SHEAF-CARRIER FOR HARVESTERS.

SPECIFICATION forming part of Letters Patent No. 341,668, dated May 11, 1886.

Application filed July 23, 1885. Serial No. 172,464. (No model.)

To all whom it may concern:

Be it known that I, JACOB V. LEYDIG, a citizen of the United States of America, residing at Greene, in the county of Butler and State 5 of Iowa, have invented certain new and useful Improvements in Sheaf-Carriers for Harvesters; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 My invention relates to certain new and useful improvements in sheaf-carriers for harvesters; and it consists in providing a harvester of this class with an endless carrying-belt or canvas upon which the sheaves are deposited, 20 and in providing shafts from which said carrying-belt is rotated, and means whereby said shaft can be thrown in and out of gear with the supporting-wheel of the harvester.

25 My invention further consists in the construction and the combination of the parts, as will be hereinafter fully set forth, and specifically pointed out in the claim.

30 In the accompanying drawings, which illustrate my invention, Figure 1 is a plan view of my improvement, and Fig. 2 is a front view showing the driving-shaft of the attachment in gear with the supporting-wheel of the harvester.

35 In the accompanying drawings, A represents a suitable rectangular frame, which is usually a portion of the frame of the binder, between the longitudinal side pieces of which is journaled the driven-wheel B, said drive-wheel having attached to the inner side thereof 40 a gear-wheel, b.

45 In front of the gear-wheel b is located a shaft, C, the end of which is provided with a pinion, c, said shaft being journaled to the frame, as shown in the drawings.

50 To the frame A is rigidly secured a supplemental frame, A', having parallel and longitudinal beams D, between which are located an endless carrying-belt or canvas, E, which is provided with parallel cross-bars, e, which 55 may be provided with upwardly-projecting teeth. This belt passes over rollers F F', the front roller, F', extending beyond one of the

side beams D, and provided at its end with a sprocket-wheel, f, over which passes a chain, G, which chain also passes over the sprocket-wheel f', which is located on the shaft C. The belt E may have side straps or chains which engage with sprocket-wheels on the rollers F F'. The sprocket-wheel f' is attached loosely to the shaft C, and is provided with a clutch, 60 i, which may be formed integral therewith. Adjacent to this clutch is located a slide or sleeve, I, having a ratchet-face which engages with the portion i. In this sleeve J is formed a groove or recess which engages a spline, so 65 that it cannot rotate upon the shaft C, and said sleeve is grooved peripherally for the reception of a spring-bar, J, which is attached to the beam of the frame, said spring-bar having a tendency to keep the sleeve I away from 70 the portion i of the clutch. The bar J has attached at its opposite or front end a connecting-rod, K, which is attached to a bell-crank, m, the opposite arm of said bell-crank being secured to the operating-bar M, by means of 75 which the bars are moved, so as to throw the clutch into engagement when desired. The longitudinal bars D D of the supplemental frame A' are provided with removable fenders D', the fenders at the inner side of the 80 frame being inclined as shown.

The operation of my invention is as follows: The sheaves or bundles of bound grain are deposited from the self-binding harvester upon the endless belt E, which is provided with 85 cross-slats, as shown, or with upwardly-projecting teeth which form rakes, the bundles being placed thereon so as to be parallel either with said slats or to the side pieces, D'. When the bundles lie parallel with the slats, the heads 90 of the straws should be adjacent to the inclined side board, D'. After a sufficient number of bundles have been placed upon this belt to form a shock, by moving the rod M the portions of the clutch will be thrown together, so 95 that the motion of the main wheel B' will be communicated through the gearing, and will cause the rotation of the endless belt, and thus deposit the sheaves upon the ground.

It will be noticed that by the arrangement of 100 the gearing as herein shown the endless belt E will rotate at a high rate of speed, and only a momentary engagement with the clutch is necessary to deposit the sheaves upon the ground.

The spring-bar J which engages with a groove in the clutch will have a tendency to keep the parts of the clutch separated, so that it will only be necessary to hold the bar M, which is 5 located near the driver's seat, momentarily.

I claim—

The combination, with the frame A and the drive-wheel B mounted thereon and carrying the gear-wheel b, and the supplemental 10 frame D D', the rollers F F', mounted thereon, and the belt E, of the shaft C, carrying the gear-pinion e, and sprocket-wheel f', the

sprocket-wheel f on roller F', drive-chain G, connecting wheels f f', the clutch i I on shaft C, the spring-bar J, holding member I away 15 from member i, the bell-crank m, and rods M K, as set forth.

In testimony whereof I affix my signature in presence of two witnesses.

JACOB V. LEYDIG.
